The ornamental design for a computer, as shown and described.

DESCRIPTION

FIG. 1 is a perspective view of a first embodiment of a computer showing our new design; and

FIG. 2 is a top plan view thereof.

FIG. 3 is a perspective view of a second embodiment of a computer showing our new design; and

FIG. 4 is a top plan view thereof;

FIG. 5 is a perspective view of a third embodiment of a computer showing our new design; and

FIG. 6 is a top plan view thereof;

FIG. 7 is an enlarged top plan view along the lines 7-7 and 7'-7' of FIG. 2;

FIG. 8 is an enlarged top plan view along the lines 8-8 and 8'-8' of FIG. 4;

FIG. 9 is an enlarged top plan view along the lines 9-9 and 9'-9' of FIG. 6; and,

FIG. 10 is an enlarged perspective view along the lines 10-10 and 10'-10' of FIG. 7.

Portions in broken lines are for illustrative purposes only and form no part of the claimed design.
